UNITED STATES PATENT OFFICE.

JOSEPH COURVILLE, OF DETROIT, MICHIGAN, ASSIGNOR TO FARRAND ORGAN COMPANY, OF DETROIT, MICHIGAN, A CORPORATION OF MICHIGAN.

KEY-STRIKER FOR PIANO-PLAYERS.

SPECIFICATION forming part of Letters Patent No. 757,889, dated April 19, 1904.

Application filed September 9, 1902. Serial No. 122,681. (No model.)

To all whom it may concern:

Be it known that I, JOSEPH COURVILLE, a citizen of the United States, residing at Detroit, in the county of Wayne and State of Michigan, have invented certain new and useful Improvements in Key-Strikers for Piano-Players, of which the following is a specification, reference being had therein to the accompanying drawings.

10 The invention relates to mechanical players for musical instruments, and more particularly to the construction of key-strikers.

The instruments to which my improvement is applicable are of that type in which the key-strikers are in the form of horizontal levers and are actuated by pneumatic motors, which in turn are controlled by a perforated music-sheet. The pneumatic motors employed are usually single-acting and are adapted to actuate the strikers to depress the keys of the instrument, the return movement being effected partly by the return-spring in the motor and partly by the return movement of the key of the musical instrument. It has been found in practice with these instruments that in the performance of music in which the keys are rapidly operated the parts are not returned with sufficient speed to be ready for successive operations.

30 It is one of the objects of my invention to provide means for returning the key-strikers independently of the return movement of the key of the instrument and of its actuating pneumatic motor.

35 It is a further object to obtain a construction which is applicable to instruments having folding key-strikers and which will not interfere with the movement of said strikers into or out of playing position.

40 The invention therefore consists in the construction as hereinafter described and claimed.

In the drawings, Figure 1 is a sectional elevation, and Fig. 2 is a perspective view, of the key-striker.

45 A is the casing of a piano-player containing the pneumatic action B, having the key-actuating pneumatics C. These pneumatics are connected by vertical push-rods D with the

key-strikers E. The latter are in the form of horizontal levers, which in their playing position are arranged with their inner ends in proximity to the upper ends of the push-rods D, while their outer ends project from the case of the musical instrument and are adapted upon actuation to depress the same. The 50 levers E are centrally fulcrumed to a bar F, preferably by means of depending bifurcated brackets G and pivot-pins H, passing through said brackets and the levers E. The bar F is connected to rock-arms H', hinged to the case 55 and so arranged that when the player is not in use said bar may be turned back, thereby carrying the key-strikers into the case.

The parts thus far described have heretofore been used and form no part of the present invention except as hereinafter specified.

In the operation of the mechanism above described the actuation of the pneumatic C will cause the upward movement of the push-rod D, which will rock the lever E, so as to depress the key. In the return movement the return-spring of the pneumatic, together with the gravity of the push-rod D, will return these parts; but the striker itself could only be returned by the actuation of the key of the musical instrument. Inasmuch as the action of the musical instrument is designed to return the key alone without other impediment it is evident that the additional work caused by the movement of the key-striker will retard the 70 quick return of the key. I have overcome this objection by providing each key-striker with a return-spring J, which is so arranged as to not interfere with the movement of the bar F when the strikers are turned back into 75 the case. The spring J, I preferably form of spring-wire, one end of which is anchored by being driven into the bracket G between the furcations thereof. From this point the spring

extends rearward and at its end is bent downward to engage with the groove K, formed near the end of the striker E. With this construction whenever the motor which has been actuated is released the tension of the spring-arm J will cause the return of the striker E 90 independently of any actuation imparted 95

thereto either by the key of the instrument or by the return movement of the motor and the rod D. Moreover, the spring J will assist in returning the rod D and motor, and, if desired, 5 the motor-returning spring may be omitted.

What I claim as my invention is—

1. In a piano-player, the combination with a horizontally-extending key-striking lever, of a fulcrum-bar therefor having at its rearward 10 side a depending bifurcated bracket, a pivot-pin for securing said lever between the furcations of said bracket, a pneumatic motor for actuating one end of said lever, and an elongated rearwardly-extended spring-arm having 15 an upwardly-extended portion engaging a slotted portion of said bracket between the furcations thereof, and bearing against the upper surface of said lever.
2. In a piano-player, the combination with 20 a horizontally-extending key-striking lever, of a fulcrum-bar therefor having at its rearward side a depending bifurcated bracket, said key-striking lever being pivoted intermediate the

furcations of said bracket, a pneumatic motor for actuating one end of said lever, and an 25 elongated rearwardly-extended spring-arm having an upwardly-extended portion engaging a recessed portion of said bracket between the furcations thereof and bearing against the upper surface of said lever.

3. In a piano-player, the combination with a key-striking lever, of a supporting-bar therefor having a depending bifurcated bracket, said key-striking lever being pivoted intermediate the furcations of said bracket, means 35 for actuating one end of said lever, and a spring-arm secured to the bracket at a point intermediate of and at the top of said furcations, said spring bearing against the upper surface of said lever.

In testimony whereof I affix my signature in presence of two witnesses.

JOSEPH COURVILLE.
